Archibald B. Hubard
BY Frank J. Besser
ATTORNEY.

UNITED STATES PATENT OFFICE.

ARCHIBALD B. HUBARD, OF OGONTZ, PENNSYLVANIA.

REINFORCED JOINT.

Application filed July 2, 1920. Serial No. 393,485.

To all whom it may concern:

Be it known that I, ARCHIBALD B. HUBARD, a citizen of the United States, residing at Ogontz, county of Montgomery, and State 5 of Pennsylvania, have invented a new and useful Improvement in Reenforced Joints, of which the following is a full, clear, and exact description, reference being had to the accompanying drawings, which form a part 10 of this specification.

My invention relates generally to reinforcing with metal an edge formed by the intersection of two surfaces, and more particularly the edges of a box or container of 15 any shape, and made of material other than metal. The general object of my invention has been to provide strength, rigidity and resistance to wear on exposed edges of paper boxes and to so reinforce them as to prevent 20 them from becoming disengaged or broken apart.

This is accomplished by drawing through the intersecting surfaces, forming an edge, a wire or metal strip of round, flat, oval or 25 triangular section at an angle to the line of joint. A single strand can be used, but I prefer to employ two strands laced in reverse directions and in which each strand is at an angle to the line of the joint, thus 30 making the reinforcing doubly strong. When the surfaces are brought to an angle with each other, the strands of wire or metal strips are bent to the same angles and run across the edge, thus strengthening 35 the edge and giving it greater rigidity and resistance to wear. The wires or metal strips intersect the surfaces on both sides of the bend and lie against both sides of these surfaces and across the bend or joint.

40 The precise nature of my invention will be best understood by reference to the accompanying drawings, which will now be described, it being premised, however, that changes may be made, without departing 45 from the spirit and scope of my invention, as defined in the appended claims.

Figure 1 is a perspective view of one form of box made in accordance with my invention.

50 Figures 2 and 3 are interior and exterior perspective views of a portion of a box.

Figure 4 is a sectional view through one form of joint before the one member is bent relative to the other portion.

Figure 5 is a similar view showing the 55 joint after it has been bent.

Figures 6, 7 and 8 are fragmentary views showing different forms of reinforcing.

In the drawings, the reference characters 10, 11 and 12, designate the bottom, ends 60 and sides, respectively, of a box in which all of the corners have been reenforced in accordance with my invention. These corners have been reenforced by a double wire lacing 13 and which may be applied as here- 65 inafter described.

If it is desired to reinforce all of the corners of a box as shown in Fig. 1, the blank from which the box is made is cut and scored in the usual manner. The joints between 70 the ends and bottom, as well as the sides and bottom, may be reenforced before the blank is folded. This is done by lacing the wire as shown in either Figs. 6, 7 and 8, and Fig. 4; and then bending the sides and ends 75 at right angles to the bottom, as shown in Fig. 5. The corners at the junctions of the ends and sides are then laced and the wire reinforce is then pressed into shape.

In Figs. 1 to 6, the reinforce 13 is formed 80 of a double lacing of approximately equal angles, while in Fig. 7 it is formed of a single lacing of equal angles.

In Fig. 8, the reinforce is also formed of a single lacing, but in this form the portion 85 14 of the lacing or one side of the structure extends approximately normal to the joint, while the portions 15 thereof, on the other side of the structure extend at an oblique angle to the joint and at an angle to the 90 normal.

The advantages of my invention result from the provision of a joint between two members having a wire reinforce interlaced through both members and shaped 95 to lie against both sides of both members.

Having now fully described my invention, what I claim and desire to protect by Letters Patent is—

1. A reenforced rigid joint between two 100 members extending at an angle to each other formed of a back and forth metal lacing passing through both members a plurality of times and lying against both sides of both members between the lacing openings 105 through both members and across the joint.

2. A reenforced rigid joint between two members extending at an angle to each other

formed of a double back and forth lacing passing through both members a plurality of times, both wires lying against both sides of both members between the lacing openings through both members and across the joint.

3. A box formed of a folded cut blank to form the ends, sides and bottom, the various members being rigidly secured to each other
10 at the junctions to form corners by back and

forth lacings passing through the members and extending over the joint on the inside and outside of the box and conforming to the shape of the box and forming braces therefor.

In testimony of which invention, I have hereunto set my hand, at Philadelphia, on this 25th day of June, 1920.

15
ARCHIBALD B. HUBARD.
